LOCOMOTIVE FIREBOX

Harry A. Hoke, Altoona, and Samuel P. Lloyd, Narberth, Pa., assignors to The Pennsylvania Railroad Company, Philadelphia, Pa., a corporation of Pennsylvania

Application April 12, 1940, Serial No. 329,242

6 Claims. (Cl. 122—71)

This invention in its broader aspects relates to fireboxes of the species including a water circulator structure disposed transversely or longitudinally of the firebox and affording support for a refractory arch, designed to promote rapid combustion in the firebox with proportionately improved water circulation in the boiler. Such structures, while operating to control or check wastage of the combustible products passing from the region of ignition to the boiler tubes, have 10 appreciably diminished the "flameway" with incidental reduction of thermic efficiency per unit of time.

The primary object of this invention is to overcome the noted objection by providing a novel 15 means whereby the length of flameway in standard type fireboxes is substantially increased, with a proportionately better consumption of the combustible products or gases arising from the source of ignition.

Another object is the provision of a novel water circulator structure and auxiliary arch which is so disposed relative to the fire bed in a locomotive firebox as to furnish an extended flameway effective to completely consume the combustible 20 matter and gases arising from said fire bed, so that the smoke box discharge is freed of all burning particles or gas.

A further object is the provision of a novel circulator and refractory arch structure of the 25 above indicated species, preferably for installation in the fireboxes of locomotives, whereby the water steaming efficiency is improved and adequate support is provided for the auxiliary arch.

With the above stated objects and ancillary advantages in view, this invention consists substantially in the novel form, arrangement and co-relation of parts hereinafter fully disclosed, illustrated by the accompanying drawings of preferred embodiments and wherein similar characters of reference are used to designate corresponding parts throughout the several views; while the concluding claims more particularly recite the features of novelty.

In the drawings:

Fig. 1 is a broken vertical longitudinal section of the firebox end of a locomotive boiler embodying a preferred form of the present invention.

Fig. 2 is a transverse vertical section on the staggered plane II—II in Fig. 1.

Fig. 3 is a similar section to the preceding, but taken on the plane III—III of Fig. 1; and,

Fig. 4 is a view like Fig. 1, but showing the adaptation of this invention to a locomotive firebox having a conventional refractory arch.

In the following detailed description of the embodiments of this invention, shown by the accompanying three sheets of drawings, specific terms will be employed for the sake of clarity; but it is to be understood that such terms are used in a descriptive sense and not for purposes of limitation. Each specific term employed herein is intended to embrace all technical equivalents which are susceptible of analogous interpretation.

For the purpose of better illustrating this invention and its application to a conventional type of locomotive firebox comprehensively designated, in all the views, as 1, and comprising side sheets 2, having a crown sheet 3, back head sheet 4 including a fire door opening 5, flue sheet 6, and rear throat sheet 7, and grate 8. The firebox 1, it will be understood, is appropriately stayed relative to the boiler outer shell comprising side sheets 9, top sheet 10, back head sheet 11, front throat sheet 12, and mud ring 13; said outer shell defining in conjunction with the firebox 1, side and back end water legs 14, 15, respectively, as well as a crown space 16 and front throat 17, all in conformity with prevailing practice.

Referring now more particularly to Figs. 1-3, inclusive, in accordance with this invention, the firebox 1 intermediate its inner ends, defined by the flue sheet 6 and back head sheet 4, is fitted with a series of longitudinally-spaced circulatory devices 18, 18', preferably as shown, in the form of inverted substantially T-shaped pipes, the leg portions 19 whereof are suitably secured at 20 into the crown sheet 3, with the arm portions 21 disposed transversely of the firebox 1 and similarly connected into the side sheets 2 at 22. It is to be here particularly noted that the leg portions 19 of the devices 18 have their upper portions vertical and their lower portions, of differing extent, inclined towards the back end leg 15 at an acute angle, while the center device 18' is provided with a diametrically reduced lower extension 23 and additional arm portions 24 in special relation below the arm portions 21 aforesaid thereby forming an inverted double-armed or Lorraine Cross device, such portions 24 being connected into the side sheets 2 at 25. In other words, it will be seen that use is made of four inverted T-shaped circulatory devices 18 with one double-armed device 18' medially located of the series, for a purpose to be later explained.

The arm portions 21 of the two forward circulatory devices 18 in conjunction with the upper arms 21 of the center device 18' jointly afford support for the forward arch 26 of refractory bricks 27; whereas the arm portions 21 of the two

rearward circulatory devices 18 in conjunction with the lower arms 24 of the center device 18' provide support for an auxiliary arch 28 of refractory bricks 29. This auxiliary arch 28, it is to be noted, extends rearwards from below the back end of the forward arch 26 with an upward inclination to a point in spacial relation below the crown sheet 3 as well as with respect to the back end sheet 4; while the front opening 30 intermediate the arms 21, 24 is of substantially less depth vertically than the opening 31 between the arms 21 and the crown sheet 3. Preferably the front arch 26 is formed with a slight longitudinal curvature, to induce a rearward or return flame flow towards the opening 30; while the auxiliary arch 28 is pitched at a slight acute angle upwards towards the back head sheet 4 from below the opening 30 or with respect to the longitudinal chord of the arch 26 so as to effect the dual purpose of checking direct passage of the flame rearwards thereover and at the same time inducing flame flow thereunder and through the opening 31, as clearly understandable by those acquainted with the art and as conventionally indicated by the arrows in Fig. 1. Thus it will be obvious that by provision of the auxiliary arch 28, the flame flow arising from the fuel on the grate 8 is considerably extended with resultant more complete consumption of the combustible content before entering the boiler flues 32, whereby the thermic effect of the firebox 1 is greatly improved and the circulatory efficiency enhanced.

The modified form of the invention shown in Fig. 4 illustrates the adaptation of the auxiliary arch 28 to a firebox 1 having a conventional arch 33, and it will be seen said auxiliary arch is consequently carried further to the back head sheet 4.

4. In this case the leg portion 19 of the forward circulatory device 18 is carried up through the rear end of the arch 33 by substitution of special notched-out refractory bricks 34; also that similar special bricks having cut-outs 35 constitute the rear row of the auxiliary arch 28, so as to define flow passage for the flame up and over said auxiliary arch, as indicated by the arrows in Fig. 4.

From the foregoing, the merits and advantages of this invention will be clearly apparent without further elaboration herein; while it is to be understood the embodiments herein disclosed are illustrative only as the invention is obviously adaptable to other than locomotive fireboxes, without departing from the spirit and scope of said invention.

Having thus described our invention, we claim:

1. In a firebox including a crown, side and throat sheets, a forward arch inclined upwardly from the throat sheet towards the back head; a series of longitudinally spaced substantially T-shape tubular transverse circulatory devices having the leg ends connected through the firebox crown, the arm portions being similarly connected

at their extremities into the side sheets, with an intervening device having vertically-spaced multiple arms; refractory brick supported by said arms to define a forward arch extending from the throat sheet to the upper arms of the intervening device, and an extension arch from said intervening device lower arms towards the firebox back end, whereby the firebox flameway is substantially increased.

2. The combination of claim 1, wherein the forward arch is longitudinally curved, and the extension arch is rearwardly and spacially inclined slightly up relative to a plane including the chord of the forward arch longitudinal curvature.

3. The combination of claim 1, wherein the intervening device multiple arms are vertically spaced and the arms of the rearmost device are positioned so as to define a flameway opening between the respective arch adjoining ends, with another flameway opening between the extension arch rear extremity and the fire box back end and crown sheets, and said openings are of different vertical height.

4. In a firebox including a crown, side and throat sheets; a forward arch inclined upwardly from the throat sheet towards the back head; inverted substantially T-shape tubular transverse circulatory devices and an associated device with additional arm portions, all of said devices having the leg ends connected through the fire box crown with the arm portions similarly connected at their outer extremities into the side sheets; and refractory brick supported by the said arm portions to define an extension arch in continuation of and spaced below the rear end of the forward arch, whereby the fire box flameway is substantially increased.

5. The combination of claim 1, wherein the intervening circulatory device embodies a diametrically reduced lower extension in alignment with the leg portion beyond the arm portions thereof, and an additional pair of arms in spacial relation below the arm portions aforesaid.

6. The combination of claim 4, wherein the leg portion of each circulatory device embodies an upright section with the lower portion rearwardly inclined at an acute angle to the vertical and said devices are graduated in height, the extension arch is angularly pitched with respect to the plane of the forward arch, the refractory brick forming the rear end of the forward arch are notched to engage the additional arm portions of the associated circulatory device in spaced relation above the forward end of the extension arch to define therewith a flameway opening, and similar refractory brick at the rear of said extension arch provide with the fire box back end and crown sheets a second relatively restricted flameway passage.

HARRY A. HOKE.
SAMUEL P. LLOYD.
